UNITED STATES PATENT OFFICE

168,958

DRESS

Jacques E. Maisch, New York, N. Y., assignor to
Burlington Mills Corporation, Greensboro, N. C.,
a corporation of Delaware

Application August 5, 1952, Serial No. 20,905

Term of patent 3½ years

(Cl. D3—26)

To all whom it may concern:

Be it known that I, Jacques E. Maisch, a citizen of the United States, residing at New York, county and State of New York, have invented a new, original, and ornamental Design for a Dress, of which the following is a specification, reference being had to the accompanying drawing, forming part thereof, wherein

Figure 1 is a front elevational view of a dress as it looks when laid out flat, embodying my new design;

Figure 2 is a rear elevational view thereof;

Figure 3 is an elevational view of the dress of Figures 1 and 2, showing the dress from the front while being worn and belted in; and

Figure 4 is a rear elevational view of the dress of Figures 1 and 2, showing the dress from the rear while being worn and belted in.

The dress is made of a plain fabric having the design shown in the drawings printed thereon.

I claim:

The ornamental design for a dress, as shown and described.

JACQUES E. MAISCH.
